UNITED STATES PATENT OFFICE

EDWIN L. HARMON, OF GROTON, NEW YORK, ASSIGNOR TO L.C. SMITH & CORONA TYPE-WRITERS INC., OF SYRACUSE, NEW YORK, A CORPORATION OF NEW YORK

TYPEWRITING MACHINE

Application filed September 25, 1928. Serial No. 308,158.

This invention relates to improvements in typewriting machines and other type printing machines having traveling paper or platen carriages and more particularly to carriage travel arresting means for such machines.

The invention has for its principal objects to provide an efficient adjustable carriage stop and stop mounting; to provide efficient right and left hand margin determining means for typewriting means; to provide adjustable margin stops for limiting endwise movements of a platen carriage which stops may be easily and quickly adjusted, will be sturdy and durable and efficient in use, and may be manufactured at low cost; and to provide a stop carrying bar and adjustable carriage stop device constructed for secure locking of the stop in different adjusted positions along the bar, and for easy release and adjustment of the stop by thumb or finger pressure on a part of the stop device.

To the above and other ends which will hereinafter more clearly appear, the invention consists of the features of construction, arrangements of parts, and combinations of devices set forth in the following specification and particularly pointed out in the appended claims.

For the purpose of illustration the invention has been shown in the drawings as embodied in a margin control mechanism for a portable three-quarter strike typewriting machine of the kind disclosed in the application of Avery, Petermann and Harmon, Serial No. 148,258, filed November 13, 1926 (now Patent No. 1,700,829, dated February 5, 1929) for arresting return movement of the carriage and for arresting advance of the carriage and locking the machine against operation. In the present instance the machine is shown provided with a sheet metal carriage and carriage bed of the kind disclosed in the application of Ely, Serial No. 198,265, filed June 11, 1927 (now Patent No. 1,741,689, dated December 31, 1929).

In the drawings:

Fig. 1 is a rear view of the platen carriage and bed of the machine looking thereat per-

pendicular to the normal plane of the rear face of the stop bar on the carriage;

Fig. 2 a top view of the parts shown in Fig. 1 looking thereat perpendicular to the normal plane of the top face of the stop bar;

Fig. 3 a fragmentary sectional view on the line 3—3 of Fig. 4;

Fig. 4 a sectional view on the line 4—4 of Fig. 1, the carriage and bed being shown tilted rearward at the angle with the horizontal which said parts make in the machine;

Fig. 5 a perspective view showing the right hand margin control stop device locked on the stop bar;

Fig. 6 a view showing the parts of the right hand margin control stop device in perspective and separated;

Fig. 7 a sectional view on the line 7—7 of Fig. 2 showing the right hand margin control stop device in locked position;

Fig. 8 a sectional view on the line 8—8 of Fig. 1, the carriage and bed being shown at the angle with the horizontal which said parts make in the machine;

Fig. 9 a view showing the parts of the left hand margin control stop device in perspective and separated;

Fig. 10 a sectional view on the line 10—10 of Fig. 2 showing the left hand margin control stop device in locked position;

Fig. 11 a sectional view on the line 11—11 of Fig. 10;

Figs. 12 and 13 fragmentary sectional views showing slightly modified forms of the right and left hand margin control stop devices, respectively, said Figs. 12 and 13 being taken on the same lines as Figs. 4 and 8, respectively; and

Fig. 14 a detail view showing the stop bar oscillating lever.

In the machine disclosed in the applications above referred to the platen carriage is mounted on the carriage bed 16 to travel transversely of the machine, antifriction bearings being interposed between the raceway flanges of the carriage and bed, and said bed being supported in the machine at the angle with the horizontal shown in Figs. 4 and 8 to support the carriage as shown in

said views for impacts of the types on the type bars of the machine upon the upper front quarter of the platen 17. The platen shaft is journalled in the end plates of the carriage, and a margin stop bar 18 extends longitudinally of the carriage a short distance above the rear edge of the carriage base plate.

The stop bar 18 is detachably held to the carriage, being provided with trunnion screws 19 journalled in the carriage end plates and threaded in the ends of the bar, and is adapted to be rocked clockwise, as viewed in Fig. 4, from its normal position shown in said view to stop clearing position by means of a hand lever 20 fixed on said bar. Said stop bar is provided about midway the ends of its front face with a notch 21 part way into which projects the rearwardly extending arm of a bracket 22 fixed to the base portion of the carriage to hold the bar against endwise movement relatively to the carriage while permitting said bar to be oscillated sufficiently to disengage the stop devices thereon from the cooperating stop devices supported from the carriage bed. The stop bar is provided with square cut notches 23 extending entirely across its front face and spaced a letter-space distance apart.

A sheet metal carriage retaining gib or bracket member 24 is held to the carriage bed by screws 25 and 25^a at the under side of the bed and has a pair of carriage retaining arms 26 curved upward and forward around the outside of the rear raceway flange of the carriage and an intermediate upwardly and rearwardly extending rigid stop arm 27. The carriage has a feed rack 28 meshing with a feed pinion 29 on a shaft 30 journalled in a bushing 31 swaged in a metal plate 32 forming part of the dog rocker supporting bracket of the machine which is rigidly held to the carriage bed. The bushing extends through an aperture in the bed and a hubbed escape-
ment ratchet wheel 41 is fixed on shaft 30 below the bushing.

The bushing 31 is stepped to provide a short, intermediate, cylindrical bearing portion 33 (indicated in dotted lines in Fig. 4) on which is pivoted a line-locking lever and carriage stop 34, the bearing portion of said lever being confined between the plate 32 and the upper end of the larger lower portion of the bushing. A spring 36 anchored to a suitable part on the carriage bed at one end is connected at its other end to lever 34 which it normally holds in the position shown in Fig. 2, with stop edge 37 of the lever against one side of the head of the screw 25, line-locking arm 38 of the lever out of locking position, and margin stop operated arm 39 of the lever to the right of the vertical, stop-engagement, left hand edge of stop arm 27 of gib 24. The head of screw 25 is thicker than that of screw 25^a so as to project into the

path of the lever 34, while arm 38 of lever 34 is offset downward to clear the thin head of screw 25^a.

The line locking lever is rockable to the position shown in Fig. 3 where it is positively arrested by engagement of stop edge 40 thereof with the side of the head of stop screw 25. In the machine referred to, movement of lever 34 into the position shown in Fig. 3 carries locking arm 38 into the throat of a hook arm of the dog rocker to lock the machine against operation, and the dog rocker is operable by the universal bar of the machine to cause escapement dogs thereon to operate with ratchet wheel 41 to feed the carriage step by step from right to left for letter-spacing, as shown and described in said application of Avery, Petermann and Harmon. The carriage is returned by a line-spacing lever, as is usual.

The foregoing parts are all constructed substantially as shown and described in the applications hereinbefore referred to and further description thereof is believed to be unnecessary to a full understanding of the present invention. The improvements as illustrated in connection with the foregoing parts of the machine will now be described.

Left and right hand margin controlling stop devices are adjustably mounted on the stop bar for cooperation with the stop devices 24 and 34, respectively, mounted on the carriage bed. Each of these stop devices on the bar consists of two members, each of the two members of each stop device being formed of a single piece of sheet metal and being entirely independent of the other member of the device, i. e. having no positive connection therewith. The abutment member of each stop device is embraced at opposite sides thereof by the locking member of the device, and said members are held in embraced relation solely by the stop bar which is passed therethrough before the bar is mounted in the carriage.

The adjustable, left hand margin controlling, stop device cooperates with stop arm 27 of member 24 to arrest return movements of the carriage toward the right hand side of the machine and consists of the locking member 42 preferably formed of thin sheet steel and the abutment member 43 formed of relatively thick sheet steel. Each of these members has a yoke-like main body portion consisting of a flat rear wall and a pair of flat forwardly extending side walls or arms. Member 42 has an integral, tempered, spring tongue extending from the rear wall 44 of its yoke portion, the free end of which presses against the rear wall 45 of the yoke portion of member 43. The side arms 46 and 47 of member 42 abut the outer faces of side arms 48 and 49 respectively, of member 43.

The side arms of member 43 are provided

with registering rectangular apertures 51 in which the stop bar 18 has a snug sliding fit. The side arms of member 42 are provided with registering rectangular apertures 51 through which the stop bar extends, the top and bottom edges of which openings slide on the top and bottom faces of the stop bar. Apertures 51 are elongated fore-and-aft so that the yoke portion of member 42 may slide fore and aft transversely of the bar, being normally pushed rearward to locking position by the pressure of the spring tongue of member 42 against wall 45 of member 43.

Preferably, as shown, only the front end of arm 47 is adapted to engage in a locking notch 28 of bar 18 when the yoke portion of member 42 is spring-pressed rearward to locking position, arm 46 being preferably folded outward away from arm 47 along the line of the front edge of its aperture 51 into parallelism with the front face of the stop bar to provide a relatively broad flat abutment lug 52 incapable of entering a locking notch and bearing flat against the front face of the stop bar when the front end of arm 47 is drawn rearward into a locking notch.

The spring tongue 53 of locking member 42 is preferably relatively narrow and of J-shape in side elevation, the short arm of the spring tongue extending upward from the middle of the upper edge of wall 44 and the long arm of the spring extending downward to a point between side arms 46 and 47 and being spaced forward of the short arm of the spring and wall 44 sufficiently to allow member 42 to be pressed forward, by thumb pressure on the rear face of wall 44, far enough to carry the front end of arm 47 out of a locking notch of the stop bar. The free lower end of spring tongue 53 is preferably provided with two oppositely and laterally extending contact arms 54 the outer ends of which are preferably bent forward as shown to contact with the rear face of wall 45 at two laterally spaced points adjacent opposite sides of the wall in the medial fore and aft plane of the stop bar, as shown. The short arm of spring tongue 53 is preferably cocked rearward out of the plane of wall 44, as shown.

The side arm 48 of abutment member 43 is formed with a flat pendant extension or contact wall 48^a merging at its rear edge with one edge of a flat pendant extension 45^a of wall 45 which extension forms a brace for contact wall portion 48^a of the abutment member. Said contact wall portion is preferably additionally braced, to further resist bending thereof under the heavy shocks to which it is subjected in arresting the usually rapid and violent return movements of the carriage, by means of a transverse brace lug 49^a extending inward from the lower edge of side arm 49 and abutting contact wall portion 48^a, said lug lying flatwise in a plane

perpendicular to the planes of both extensions 45^a and 48^a, and abutting at its free end the face of extension 48^a opposed to that face of said extension which engages the vertical or straight left hand stop edge of stop arm 27.

The adjustable, right hand margin controlling, stop device is of substantially the same construction as the adjustable, left hand margin controlling, stop device just described and a brief description thereof with reference to the parts of the left hand margin stop device will be sufficient. This stop consists of the locking member 55 and abutment member 56 formed, respectively, of relatively thin and thick sheet steel, each in a single piece. Member 55 has the yoke-like body portion formed of rear wall 57 and side arms or walls 58 and 59, similar, respectively, to wall 44 and arms 46 and 47 of member 42. Arms 58 and 59 are provided with apertures 67 similar to apertures 51, and arm 58 is formed with a laterally bent forward end portion or abutment lug 60 similar to portion 52. Wall 57 is formed with an integral J-shaped spring tongue 61 with lateral arms 62 having forwardly bent contact ends similar to spring 53 and arranged and coactive with rear wall 63 of the yoke portion of member 56 in the same manner as spring 53 is arranged and coacts with wall 45.

The yoke portion of member 56 consists of the flat rear wall 63 and side arms or walls 64 and 65 similar to wall 45 and arms 48 and 49 of member 43, except that neither side arm has a pendant extension while the rear wall has a pendant extension or contact portion 66, the left hand edge of which coacts with the right hand edge of the rearwardly projecting contact head portion 39^a of arm 39, of the carriage stopping and line-locking lever 34.

It is unnecessary to provide a braced, pendant, contact portion for the right hand margin stop device since this device arrests the carriage in its step by step letter-feed movement from right to left under control of the escapement and is not, therefore, subjected to heavy shocks. Arms 64 and 65 are provided with apertures 68 similar to apertures 50 of member 43, and the yoke portion of member 56 is embraced by the yoke portion of member 55 when the device is assembled on the bar.

The stop bar 18 has letter space scale graduations 69 and associated numerals 70 stamped in its rear face. These numerals and graduation markings terminate short of the top and bottom edges of the rear face of the bar and the rear edges of the apertures in the members of the stop devices are preferably cut back as indicated at 71 to clear said numerals and markings. The elongated bar apertures in the locking members may be extended sufficiently to the rear to preclude 120

engagement of the rear edges of said apertures with the rear face of the bar when the springs are fully compressed, if desired. The arrangement shown is preferred, however, the foremost edge portions of the stepped rear edges of the apertures in the locking members engaging the rear face of the bar after the locking member is released to prevent crushing or flattening out of the bent extensions 54 and 52 of the J-shaped springs under heavy forward thumb pressures. The rear face of the rear wall of each locking member is preferably knurled, as shown in Fig. 1, to facilitate sidewise shifting of the stop devices from one adjusted position to another by the thumb of the operator while the locking members are held pressed forward in released position by the thumb pressure.

In Fig. 12 a slightly modified form of adjustable, right hand margin controlling, stop device 72 is shown, and in Fig. 13 a slightly modified form of adjustable, left hand margin controlling, stop device 73 is shown. These stop devices are constructed precisely like the corresponding stop devices shown in the other views, except that the J-shaped springs are formed integrally with the lower edges of the rear walls of the locking members of the stop devices.

The described construction wherein each stop device consists solely of two independent members, each formed of a single piece of sheet metal and having no positive connection therebetween, one of said members constituting the abutment or contact element and the other member constituting the adjusting and locking element of the stop device, affords a simple, light, and inexpensive stop device. It will be observed also that the stop devices are easily releasable and adjustable by finger pressure, and that the only part of a stop device that is flexed in releasing is the integral spring tongue.

The construction and arrangement of this integral spring tongue, shown and described is advantageous in that a narrow highly flexible tongue is provided, shaped and arranged to afford a spring of great resilience but of compact form and in compact relation with the other portions of the stop device. The construction and arrangement of the spring and the parts of the stop device are also such that spring pressure is so distributed as to prevent cocking of the abutment member on the bar when the locking member is pressed into releasing and adjusting position which would cause binding of the abutment member on the stop bar greatly resisting or preventing adjustment of the stop device. The normal rearward cocking of the J-shaped spring relatively to the planes of the rear walls of the two members of the stop device allows full flexing of the spring without the spring striking the upper edge of the rear wall of the abutment member and thereby

lessening the resilient force exerted on said abutment member.

It will be observed that the non-locking side arms 46 and 58 of the two stop devices are at the inner sides of these two devices, i. e. at the sides nearest the middle of the carriage, while the locking arms 47 and 59 are at the outer sides of the devices. By this arrangement the locking arm of each device is backed up by the adjacent abutting side arm of the abutment member of the device so that it will not bend under stopping strains. By providing but one locking arm difficulty and expense of precision manufacture which would be required to provide for entrance of both arms of the locking member of a stop in different notches in a bar are avoided. Furthermore it will be obvious that the inner arm of the locking member would be too weak to hold in a notch under stopping strains unless made heavy and stiff since it would not be backed by a part of the abutment member to take stopping strains.

The provision of a second non-locking arm on the locking member constructed as shown and described is advantageous, however, in that the locking member is thus accurately guided in its movements both transversely and longitudinally of the stop bar, this non-locking arm being precluded from engaging in the notches of the bar at any time by the lateral extension or lug at its front end and acting to resist cocking of the locking and abutment members of the stop device when the stop device comes in engagement with its cooperating stop on the carriage bed.

As the carriage approaches the end of its letter-feed travel from right to left for which the right hand margin controlling stop device on bar 18 is adjusted, the left hand edge of contact portion 66 of said device engages the right hand edge of contact head 39^a of arm 39 of lever 34 and rocks said lever from the position shown in Fig. 2 to that shown in Fig. 3 against the pull of spring 36, whereupon lever 34 is arrested by the head of screw 25, thus stopping the carriage with line-locking arm 38 of lever 34 in its machine-locking position. Upon return of the carriage from left to right, the right hand face of contact wall 48^a of the left hand margin controlling stop device on bar 18 engages the straight left hand edge of stop arm 27 of gib 24 on the carriage bed and immediately arrests the carriage. The pendant portions 45^a and 48^a of this stop device are made short as shown to permit the same to pass over head 39^a of lever 34, while pendant portion 66 of the other stop device is adapted to pass behind stop arm 27. Either adjustable stop device may be swung to clear its cooperating stop for typing within the marginal areas by rocking the handle portion of lever 20 forward. Lever 20 has a pendant stop arm 74 normally held by the weight of the stops, aided if de-

sired by a suitable return spring for the stop bar, against a stop portion 75 of the carriage. Said lever is also preferably provided with a second stop arm 76 adapted to rock downward into engagement with the bottom of the carriage to limit the extent of stop-releasing rocking movement of the stop bar 18. It will be noted that the major portion of the weight of the stop devices is in rear of the vertical plane of the bar axis.

By making the abutment member of each stop device of substantially thicker sheet metal stock than the locking member of the stop device, the side arms of the abutment members may be made flat without danger of engagement thereof in the notches of the stop bar. The heavy gauge stock of the abutment members also affords strong abutment portions for the stop devices which will not be bent out of shape in operation, and these strong rigid abutment members back up or brace the thin locking side arms of the locking members.

What I claim is:

1. In a typewriting machine, the combination of a traveling platen carriage, a margin stop bar on the carriage of rectangular cross-section and having stop-locking notches extending transversely of one face thereof spaced a letter-space distance apart, and a pair of margin stop devices mounted on said bar for adjustment therewith and locking thereto, each of said stop devices consisting solely of an abutment member and a combined adjusting and locking member each formed of a single piece of sheet metal, the two members having yoke-like, rigid, main body portions the side arms of which have registering apertures through which the bar extends and the transverse parts of which are located at the opposite face of the bar from the notched bar face, the body portion of the locking member embracing the body portion of the abutment member, the side arms of the abutment member being of greater thickness than the width of the bar notches and the apertures therein being shaped to prevent relative transverse movement between the member and bar, one side arm of the body portion of the locking member being engageable in the bar notches and the apertures in the side arms of said member being shaped to permit shifting of the rigid body portion thereof in a path perpendicular to the plane of the notched face of the bar only, the transverse part of the body portion of the locking member being formed with an integral spring tongue bearing against the transverse part of the body portion of the abutment member and normally yieldably holding the locking member in locking position, the left hand margin stop having a contact wall for engaging a fixed stop formed as a pendant extension of one side arm of its abutment member, said contact wall being

braced by an integral lug extending laterally from the other side arm of the abutment member.

2. In a typewriting machine having a traveling carriage, the combination of a carriage stop carrying bar of rectangular cross-section having transverse notches in one face thereof, and a carriage stop mounted on and adjustable along said bar, said stop comprising an abutment member having a rigid yoke-like body portion slidable along said bar and a locking member having a rigid yoke-like body portion embracing the body portion of the abutment member slidable along said bar and also slidable transversely of the bar perpendicular to the notched face of the bar into and out of engagement with the bar notches to lock the stop against movement along the bar, the transverse parts of the yoke-like body portions of the stop members being spaced apart and located at the opposite face of the bar from the notched bar face, and the transverse part of the yoke-like body portion of the locking member being formed with an integral J-shaped spring tongue the shorter arm of which is joined with an edge of said part extending longitudinally of the bar and the free end of the longer arm of which extends between the side parts of the yoke-like body portion of said member and between the transverse parts of the yoke-like portions of the two members and is formed with a pair of wings extending in opposite directions longitudinally of the stop bar and bent toward the stop bar to bear at their ends against the transverse part of the abutment member to yieldably hold the locking member in stop-locking position.

3. In a typewriting machine having a traveling carriage, the combination of a carriage stop carrying bar of rectangular cross-section having transverse notches in one face thereof, and a carriage stop mounted on and adjustable along said bar, said stop comprising an abutment member having a rigid yoke-like body portion slidable only along said bar and a locking member having a rigid yoke-like body portion embracing the body portion of the abutment member slidable along said bar and also slidable transversely of the bar solely in a path perpendicular to the notched face of the bar into and out of engagement with the bar notches to lock the stop against movement along the bar, said bar passing through the side parts of the yoke-like body portions and being the sole element holding said members in operative relation, the transverse parts of the yoke-like body portions of the stop members being spaced and located at the opposite face of the bar from the notched bar face, and the transverse part of the yoke-like body portion of the locking member being formed with an integral spring tongue bearing at its free end against a surface of the transverse part of the yoke-

like body portion of the abutment member facing in a direction opposite to that in which the notched face of the bar faces, the yoke-like body portion of the abutment member having an integral rigid contact part extending therefrom and an integral brace engaged with said contact part.

4. In a typewriting machine having a traveling carriage, the combination of a carriage stop carrying bar of rectangular cross-section having transverse notches in one face thereof, and a carriage stop mounted on and adjustable along said bar, said stop comprising an abutment member having a rigid yoke-like body portion slidable along said bar and a locking member having a rigid yoke-like body portion embracing the body portion of the abutment member slidable along said bar and also slidable transversely of the bar perpendicular to the notched face of the bar into and out of engagement with the bar notches to lock the stop against movement along the bar, the transverse parts of yoke-like body portions of the stop members being spaced and located at the opposite face of the bar from the notched bar face, and the transverse part of the yoke-like body portion of the locking member being formed with an integral spring tongue bearing at its free end against a surface of the transverse part of the yoke-like body portion of the abutment member facing in a direction opposite to that in which the notched face of the bar faces, the yoke-like body portion of the abutment member having an integral rigid contact part extending downward from the lower edge of one side part of said portion for movement against a cooperating stop and braced against impact thrusts by an integral lug which extends longitudinally of the bar from the lower edge of the other side part of said portion into engagement with said contact part, and further braced by a downward extension of the transverse part of said portion which forms with said contact part an integral angular pendant extension of said portion.

5. In a typewriting machine having a traveling carriage, the combination of a carriage stop carrying bar of rectangular cross-section having transverse notches in one face thereof, and a carriage stop mounted on and adjustable along said bar, said stop comprising an abutment member having a rigid yoke-like body portion slidable along said bar and a locking member having a rigid yoke-like body portion embracing the body portion of the abutment member slidable along said bar and also slidable transversely of the bar perpendicular to the notched face of the bar into and out of engagement with the bar notches to lock the stop against movement along the bar, the transverse parts of yoke-like body portions of the stop members being spaced and located at the opposite face of the bar from the notched bar face, and the transverse part of the yoke-like body portion of the locking member being formed with an integral spring tongue bearing at its free end against a surface of the transverse part of the yoke-like body portion of the abutment member facing in a direction opposite to that in which the notched face of the bar faces, the yoke-like body portion of the abutment member having an integral rigid contact part extending downward from the lower edge of one side part of said portion for movement against a cooperating stop and braced against impact thrusts by an integral lug which extends longitudinally of the bar from the lower edge of the other side part of said portion into engagement with said contact part.

6. In a typewriting machine having a traveling carriage, the combination of a carriage stop carrying bar of rectangular cross-section having transverse notches in one face thereof, and a carriage stop mounted on and adjustable along said bar, said stop comprising an abutment member having a rigid yoke-like body portion slidable along said bar and a locking member having a rigid yoke-like body portion embracing the body portion of the abutment member slidable along said bar and also slidable transversely of the bar perpendicular to the notched face of the bar into and out of engagement with the bar notches to lock the stop against movement along the bar, the transverse parts of yoke-like body portions of the stop members being spaced and located at the opposite face of the bar from the notched bar face, and the transverse part of the yoke-like body portion of the locking member being formed with an integral spring tongue bearing at its free end

against a surface of the transverse part of the yoke-like body portion of the abutment member facing in a direction opposite to that in which the notched face of the bar faces, the yoke-like body portion of the abutment member having an integral rigid contact part extending downward from the lower edge of one side part of said portion for movement against a cooperating stop and braced against impact thrusts by an integral lug which extends longitudinally of the bar from the lower edge of the other side part of said portion into engagement with said contact part, and further braced by a downward extension of the transverse part of said portion which forms with said contact part an integral angular pendant extension of said portion.

6. In a typewriting machine having a traveling carriage, the combination of a margin stop carrying bar on the carriage of rectangular cross-section having transverse stop-locking notches in one face thereof, and a margin stop mounted on said bar and adjustable therealong, said stop comprising abutment and locking members each formed from a single piece of sheet metal, said members having non-resilient body portions of yoke-like form each comprising a flat transverse wall parallel with the notched face of the bar and located at the opposite side of the bar from the notched face and parallel flat side walls through registering apertures in which the bar extends, the body portion of the locking member embracing the body portion of the abutment member with the side walls contacting and the transverse walls spaced apart, the apertures in the side walls of the abutment member being shaped to prevent transverse movement of said member relatively to the bar and the side walls thereof being too thick to enter the bar notches, the apertures in the side walls of the locking member being shaped to permit transverse movement of the body portion of said member transversely of the bar only in a direction perpendicular to the plane of the notched bar face, the free end of one of the side walls of the locking member being adapted to enter the bar notches and the free end of the other side wall of the locking member being bent outward to form an abutment wider than the bar notches adapted to bear against the notched bar face when the first-mentioned wall engages in a bar notch, the non-locking side wall being located at the leading side of the stop, and the transverse wall of the locking member being provided with an integral spring tongue bearing against the adjacent face of the transverse wall of the abutment member between the side walls of the locking member.

7. In a typewriting machine having a traveling carriage, the combination of a margin stop carrying bar on the carriage of rectan-

gular cross-section having transverse stop-locking notches in one face thereof, and a margin stop mounted on said bar and adjustable therealong, said stop comprising abutment and locking members each formed from a single piece of sheet metal, said members having non-resilient body portions of yoke-like form each comprising a flat transverse wall parallel with the notched face of the bar and located at the opposite side of the bar from the notched face and parallel flat side walls through registering apertures in which the bar extends, the body portion of the locking member embracing the body portion of the abutment member with the side walls contacting and the transverse walls spaced apart, the apertures in the side walls of the abutment member being shaped to prevent transverse movement of said member relatively to the bar and the side walls thereof being too thick to enter the bar notches, the apertures in the side walls of the locking member being shaped to permit transverse movement of the body portion of said member transversely of the bar only in a direction perpendicular to the plane of the notched bar face, the free end of one of the side walls of the locking member being adapted to enter the bar notches and the free end of the other side wall of the locking member being bent outward to form an abutment wider than the bar notches adapted to bear against the notched bar face when the first-mentioned side wall engages in a bar notch, the non-locking side wall being located at the leading side of the stop, and the transverse wall of the locking member being provided with an integral spring tongue bearing against the adjacent face of the transverse wall of the abutment member between the side walls of the locking member, said spring tongue being of J-shape and relatively narrow with its shorter arm joining the transverse wall of the locking member midway the ends of one longitudinal edge of the wall and having lateral wings on its free end bent toward and bearing against said face of the transverse wall of the abutment member at spaced points in line with the stop bar.

In testimony whereof I hereunto affix my signature.

EDWIN L. HARMON.
